Primary Examiner — Cynthia R Underwood(74) *Attorney, Agent, or Firm* — Stratford Managers Corporation(57) **CLAIM**

The ornamental design for a cable retainer, as shown and described.

DESCRIPTION

FIG. 1 is a left side view of the cable retainer in an unengaged position. The cable retainer is shown mounted within a network appliance box that is connected to a cable. FIG. 2 is an isometric view of the cable retainer from the front.

FIG. 3 is an isometric view of the cable retainer from the rear.

FIG. 4 is a top view of the cable retainer.

FIG. 5 is a side view of the cable retainer from the right.

FIG. 6 is a front view of the cable retainer.

FIG. 7 is a bottom view of the cable retainer.

FIG. 8 is a rear view of the cable retainer.

FIG. 9 is a side view of the cable retainer from the left; and, FIG. 10 is a left side view of the cable retainer in an engaged position. The cable retainer is shown mounted within a network appliance box that is connected to a cable.

The broken lines represent unclaimed environmental subject matter and form no part of the claimed design.

1 Claim, 5 Drawing Sheets(56)
